UNITED STATES PATENT OFFICE.

WALTER M. BOEHM, OF IOWA CITY, IOWA.

CALCULATING-MACHINE.

No. 870,009.

Specification of Letters Patent.

Patented Nov. 5, 1907.

Application filed April 6, 1907. Serial No. 366,776.

To all whom it may concern:

Be it known that I, WALTER M. BOEHM, a citizen of the United States, residing at Iowa City, in the county of Johnson and State of Iowa, have invented a new and 5 useful Calculating-Machine, of which the following is a specification.

This invention has reference to improvements in calculating machines, and its object is to produce a machine of few parts and of simplicity of operation 10 but which will be efficient and certain in action.

The invention consists essentially of a suitable casing containing a number of movable members each having a range of movement sufficient to comprise a series of numbers, say, from one to ten, and means 15 actuated by these members for moving number drums to a corresponding extent to exhibit the numbers to view, with certain mechanisms whereby these operations are performed without complexity of structure or gearing or other expensive parts which add to the cost 20 of machines of this character.

The invention also comprises a simple means whereby the entire set of index drums may be moved to the zero position whenever the operator so desires.

The invention will be fully understood from the following detailed description taken in connection with the accompanying drawings forming part of this specification, in which,

Figure 1 is a perspective view of the exterior of the improved calculating machine; Fig. 2 is a central vertical section therethrough; Fig. 3 is a section on the line $x-x$ of Fig. 2, looking toward the rear; Fig. 4 is a top plan view of the interior mechanism, with parts of the casing removed and other parts broken away and shown in section; Fig. 5 is a detail view of one of the 30 index drum actuating mechanisms immediately adjacent to said drum; and Fig. 6 is an elevation of a number of adjacent structures such as shown in Fig. 5.

Referring to the drawings, there is shown a suitable casing 1, the lower portion 2 of which is offset toward 40 the front and from there has a general rearward slant toward the top 3, which latter is comparatively narrow. The front of the casing immediately above the projecting portion 2 is segmental in shape and is there open to the interior of the casing, this opening containing a number of curved division strips 4 fast upon a cross-piece 5 at the upper end of the segmental portion of the casing and upon inwardly-projecting division blocks 6 secured to the inside face of the upright front portion 2 of the casing. The strips 4 and division 45 blocks 6 are spaced apart to constitute curved parallel slots in the curved front of the casing and extending across the same. The adjacent edges of the strips 4 and also the sides of the casing form guiding runways for segmental pivoted plates 7 constituting the finger- 50 actuated operating levers of the machine. These levers, which, in the particular instance shown in the

drawings are eight in number, are pivoted at their smaller ends upon a fixed rod 8 extending across the machine near the rear thereof and finding support in the two sides of the casing 1. The front ends of the levers 7 are curved concentric with the curve of the strips 4 and project slightly beyond the same where they are formed with finger-pieces 9, which in the drawings are shown as triangular in shape with their flat faces uppermost and the inclined face of one meeting the flat face of the next lower finger-piece. It will be understood, of course, that any other type of finger-piece may be used, whether the same be a simple straight piece of metal, or be cup-shaped to conform to the shape of the finger-tip, or otherwise shaped, as may be desired, 60 so long as it is adapted to receive the finger of an operator in order that he may move the lever around its pivot 8 when the finger is placed on the upper side of one of the finger-pieces 9 and pressure is applied to depress the lever. These finger-pieces 9 are appropriately numbered so that the operator may place his finger upon the desired finger-piece. For instance, there are nine finger pieces shown and they are numbered from one to nine, counting from the lowermost to the uppermost, the numbers, however, being shown 65 on the inclined faces, but may be placed directly on the finger-pieces. The arrangement is such that when the operator places his finger upon, say, the first finger-piece and depresses the lever until the finger strikes the offset portion 2 of the casing, the lever will be 70 moved a distance sufficient to operate, in a manner that will hereinafter appear, a suitable index a distance sufficient to expose the number 1, assuming that the index had been set at zero. If the operator shall put his finger upon another finger-piece 9, say, that corresponding to the number 5, and shall depress the lever until his finger hits the projecting portion 2 of the casing, the index will be moved to five if it were set at zero, or to six if it had already been operated to indicate one, and so on.

It will be understood that the distance from the pivot point 8 of the levers 7 to the outer edge of the finger-pieces 9 is such that these finger-pieces will pass into the casing behind the rear edge of the front 2, so that wherever a finger may be placed upon a finger-piece 100 all those below the finger-piece engaged will pass into the casing out of the way, and the lever will always be stopped by the engagement of the finger with the upper edge of the front 2. Each lever 7 is constrained to assume the position shown in Figs. 1 and 2 with its upper edge abutting against the lower edge of the cross-piece 5 by a spiral spring 10 provided at its upper end with a yoke 11 passing around the lever in front of the pivot 8 and engaging a notch 12 on its lower edge, the upper end of the spring being fast to the rear portion 105 of the casing near its upper end by an eye 13 or other suitable fastening device. When the lever is depressed

by the operator it is against the action of this spring which is put under tension by such movement of the lever, and when the operator releases the lever the spring immediately returns it to the upper normal position shown in the drawings.

Between the top 2 and that portion of the casing occupied by the levers 7, the casing has an inclined cover 14 provided with a lateral series of openings 15 beneath which is arranged a lateral series of index drums 16 all mounted to turn freely upon a shaft or bar 17 fast in the sides of the casing. These index drums are best shown in Figs. 5 and 6, being there shown upon a larger scale than in the other views. Each drum is provided with a hub 18 projecting to a greater extent upon one side of the drum than on the other, and this hub turns freely upon the shaft or bar 17. Fast on the hub on the elongated side thereof is a ratchet wheel 19 turning with the drum, and near the periphery of the drum on the side thereof opposite the ratchet wheel is a laterally projecting pin 20. There are as many drums as there are levers 7 and these drums are placed upon the rod or shaft 17 with their hubs in abutment and are maintained in this position by end-collars 54, fast upon the rod or shaft 17, which prevent lateral displacement of the drums but do not interfere with their free rotary movement upon the shaft 17. Each of these drums is provided upon its periphery with suitably spaced numbers from zero to nine, and the ratchet wheels 19 have a corresponding number of teeth.

Each ratchet wheel is normally held from rotation in one direction by a dog or pawl 21 mounted for free movement upon a fixed cross-rod 22 supported at its ends in the sides of the casing. One side of each pawl 21 adjacent to its pivot support is provided with a deep groove or notch 23, and the pawl is constrained to remain in engagement with the ratchet teeth by a suitable spring 24, one end of which is in fixed relation to another cross-rod or bar 25 extending across the machine and finding support in the sides of the casing.

Instead of the particular form of spring 24 shown in the drawings, it will be understood that an ordinary helical spring may be used for keeping these pawls normally in engagement with the ratchet teeth. In the notch 23 of each pawl there is secured the upper end of a rod 26 which, as best shown in Fig. 2, extends downwardly and rearwardly and is there secured to a cross-bar 27 located to the rear of the pivotal support 8 of the levers 7, and the ends of the bar 27 adjacent to the sides of the casing are bent parallel thereto to constitute arms 28, the free ends of which are pivoted at 29 to the sides of the casing, so that this bar may be moved on its pivots to draw all the pawls 21 out of engagement with all the ratchets 19. When the bar 27 is moved as will herein-after appear, downwardly, all the pawls 21 are moved out of engagement with the ratchets and at the same time their springs 24 are put under tension and when the bar 27 is released from the mechanism which causes it to move downward the springs 24 cause it to return to the upper position, thus releasing the pawls 21 and allowing them to move into engagement again with the ratchet wheels 19. The purpose of this operation will herein-after appear. Near the rear of the casing there is another cross-bar 30 upon which are mounted a number of bell-crank levers 31, the shorter arms 32 of which are connected by helical springs 33 to the

cross-bars 22 before referred to. The normal tendency of the springs 33 is to maintain the longer arms of the levers 31 in upright position about parallel with the rear wall of the casing, and from the upper end of each of these levers there extends a chain 34 over the ratchet wheel and from thence over a fixed cross-rod 35 fast in the side walls of the casing, and the end of the chain is coupled by means of a link 36 to a U-shaped strap 37 straddling the lever 7 and pivotally connected thereto by a pivot pin 38. The lever 7 may be notched or cut away at this point to accommodate the strap 37, or the latter may be made sufficiently long to avoid the cutting away of the lever 7, as desired.

It will now be seen that when a lever 7 is depressed the chain 34 will be moved with the lever pulling the bell-crank lever 31 with it against the action of the spring 33. The links of the chain 34 will engage the teeth of the ratchet wheel 19 and the latter, together with the drum 16, will be caused to rotate in the direction permitted by the pawl 21. The index drum 16 is therefore, by means of the chain and connections to the lever 7, rotated a distance corresponding to the movement of the lever 7, the parts being properly proportioned for this operation. When, however, the lever is returned to its normal position the spring 33, acting through the bell-crank lever 31, will return the chain to its first position, but as the ratchet wheel 19 is held against reverse rotation by the pawl 21, the chain will simply ride over the teeth in returning to its initial position. Besides serving to return the chain to its initial position, the spring 33 also maintains this chain at all times in a taut condition.

In order that each complete rotation of an index drum 16 may impart to the next succeeding index drum of the series a rotation equal to one digit which, as will be readily understood, represents the ten digits or one complete rotation of the preceding index drum, I have provided a special mechanism which I will now proceed to describe. Pivotally supported upon the cross-rod 25 are a number of plates 39, each having one portion extending below said rod 25 and there connected by a helical spring 40 to another fixed rod 41 extending across the casing and finding support in the side walls thereof. Above the pivotal support 25 each plate 39 is forked to form two fingers 42-43, the finger 42 being normally in the path of the pin 20 upon a drum 16 and the finger 43 being bent toward the next adjacent drum and there carrying a pawl 44 having a tooth 45 arranged to engage the ratchet wheel 19 of the said next adjacent drum. This pawl 44 is held in normal engagement with the respective ratchet wheel by a helical spring 46 connected at one end to the pawl 44 and at the other end to the cross-bar 25. The pawl 44 on the side of its pivot opposite the spring 46 and next to the tooth 45 is connected by a rod 47 to the bar 27 before described, so that all of the pawls 44 as well as all of the pawls 21 are disconnected from their respective ratchet wheels 19 by the movement of the bar 27 when the latter is depressed.

When an index drum has been rotated until its pin 125 comes in contact with the finger 42 of the plate 39 adjacent thereto, the next impulse given to the drum will cause it to move the plate 39 about its pivot, and, therefore, through the pawl 44 cause the next succeeding ratchet 19 and drum 16 to be moved a distance equal 130

to the space of one tooth, so that while the first drum may in its movement be designating units it will, after having made one complete rotation, have moved the next drum a distance equal to one unit, but which movement will designate a movement equal to ten units by the first drum; and through this mechanism each succeeding index drum will move the next succeeding index drum a distance of one unit to indicate the movement of the preceding drum a distance equal to ten of the units indicated by the latter.

It will now be seen that in order to register any number upon the machine, the number of units will be indicated by the movement of a right-hand lever a distance corresponding to those units, tens will be indicated by the second lever, hundreds by the third lever, and so on. Where it is desirable to find the sum of several numbers, it is only necessary to register on the appropriate levers the figures representative of the units, tens, hundreds, etc., found in said numbers, 20 when through the slots 15 the sum of these numbers may at once be read.

When the sum of any series of numbers desired has been ascertained, it then becomes necessary to reset the machine to the zero position. For this purpose 25 there is mounted upon the pivot rod 8 adjacent to the side walls of the casing two arms 48 extending upward to a point near the upper faces of the levers 7 and just behind the strips 4, where these arms are joined by a cross-piece 49, integral therewith or which may be 30 secured thereto. Secured at the middle of the cross-piece 49 there is a handle 50 extending to the front of the machine through one of the slots formed between the strips 4 and normally resting in a notch 51 formed in the cross-piece or pieces 5. The lower ends of the 35 side bars 48 extend below the pivot points 8 and are in the path of the arms 28 before referred to so as to constitute stops limiting the upward movement thereof. These lower ends of the bars 48 are also formed with cam projections 52 which, when the bars are 40 moved about their pivots by the proper manipulation of the handle 50, will engage the arms 28 and cause the depression of the bar 27 to operate the pawls 21 and 44 as before described. When the handle 50 is drawn downward the cross-piece 49 will engage all the levers 45 7 and move them simultaneously. The purpose of the frame composed of the side bars 48 and cross-piece 49 being to reset the machine, the handle 50 should be so manipulated as to move the levers 7 downward to the full extent of their movement. This will cause all 50 the index drums to be rotated and at the same time will release the pawls 21 and 44 from engagement with the ratchet wheel 19. When the handle 50 is released the several springs will return the parts to their normal condition. This will cause, first, the reverse rotation 55 of the several ratchet wheels 19 by the chains traveling over them, since they have been disengaged by the pawls holding them and are therefore free to be rotated backward by the chains. This backward movement, however, is stopped as soon as the pins 20 on the drums 60 have come in contact with the fingers 42 in their paths and whatever further distance the chains may have to move they will simply ride over the teeth of the ratchet wheels without moving them. The ratchet wheels and drums will therefore be all stopped at the same 65 point and this prior to or just coincident with the re-

engagement with the ratchet wheels of the pawls 21 and 44, the movement of the parts being so timed as to provide for such operation. The index drums will now all register zero and the machine is therefore in condition to be again used in the manner heretofore described.

The curved strips 4 serve as guides for the front ends of the levers 7, and, therefore, in order to prevent undue wear these levers at this point may be provided with cheek plates 53 which will form wear surfaces for contact with the edges of the strips 4, especially where the levers 7 are made of wood or other soft material.

It may be observed that the plate 39 situated at the extreme left, that is, beyond the last index drum, does not carry any pawl 44 but has a finger 42 for engagement with the pin 20 of this last index drum, so as to provide for resetting it as heretofore described.

I claim:

1. In a calculating machine, a series of index drums arranged for indicating successively higher denominations, 85 a series of operating levers, one for each denomination embraced in the series of index drums and each having an extent of movement sufficient to comprise the digits of the denomination it represents, means for normally holding each drum against reverse movement, and flexible connections fast to and movable in both directions with the operating levers, said connections rotating the drums when moved in one direction and normally passing idly by said drums when moved in the other direction.

2. In a calculating machine, a series of index drums, 95 each independently rotatable, a ratchet wheel secured to and movable with each drum, operating levers, one for each drum and movable for a distance commensurate with the number of digits carried by each drum, a chain connection between each lever and the toothed periphery of the 100 respective ratchet wheel for moving said wheel and drum with said lever, and means for normally preventing the reverse movement of the ratchet wheel when the lever is returned to its normal position.

3. In a calculating machine, a series of rotatable index 105 drums, ratchet wheels, one for each drum and each connected to its respective drum for rotation therewith, operating levers for causing the rotation of the drums in one direction, chain connections, each secured at one end to one of the levers and passing over and in engagement with the teeth of the respective ratchet wheel, springs connected to the other ends of said chain connections to maintain them taut and to return them to their normal positions, and means for normally holding the ratchet wheels against reverse rotation when the levers are returned to 110 their normal positions.

4. In a calculating machine, operating levers, chains connected at one end to the levers, means at the other ends of the chains for maintaining them in a taut condition under movement, rotatable index drums, ratchet wheels, one 120 for each drum and each connected to its respective drum for rotation therewith, said ratchet wheels being engaged by the chains at points intermediate of the length of the chains, and means for normally holding the ratchet wheels against reverse rotation when the levers and chains are 125 returned to their normal positions.

5. In a calculating machine, operating levers, rotatable index drums, ratchet wheels, one for each drum and each connected to its respective drum for rotation therewith, means for normally holding the drums against movement 130 except in one direction, and chain connections fast to the levers and engaging the teeth of the ratchet wheels when the chains are moved in one direction to rotate said ratchet wheels and passing idly over the said teeth of the ratchet wheels when the chains are moved in the other direction and the ratchet wheels are locked against reverse rotation.

6. In a calculating machine, a series of index drums, a ratchet wheel fast on each drum, operating levers, one for each drum, flexible connections secured to the levers and 140 passing over the ratchet wheels for positively engaging

- the teeth of the same only when the levers are moved in one direction, pawls normally in engagement with the ratchet teeth for preventing the reverse movement of the drums, and means for communicating motion from one 5 drum to the next adjacent drum comprising a pin on one drum, a spring-controlled pivoted support having a finger in the path of said pin and a pawl also carried by said plate in the path of the teeth of the ratchet wheel of the next adjacent drum.
- 10 7. A calculating machine comprising a series of index drums, ratchet wheels, one for each drum and fast thereto, a series of operating levers, one for each drum, chain connections between each lever and the ratchet wheel of the respective drum and positively engaging the teeth of the 15 ratchet wheel when the drum is moved in one direction; pawls normally engaging the ratchet wheels to prevent reverse rotation thereof, connecting means between the drums each comprising a finger in the path of the pin of a drum and a pawl in the path of the teeth of the next 20 adjacent ratchet wheel, and means for moving the pawls out of engagement with the ratchet wheels and for moving all the levers simultaneously to the full extent of their movement and for then permitting them to return simultaneously to their initial position to reset all the index 25 drums to the zero position.
8. In a calculating machine comprising index drums rotatable in both directions, locking mechanism for normally holding the drums against rotation in one direction, means for rotating all the drums simultaneously in the forward direction, means for releasing the drums from their normal locking mechanism actuated by the first-named means, means for causing a reverse simultaneous rotative movement of the drums, and means for arresting the reverse movement of each drum when it reaches the zero position.
- 30 9. In a calculating machine, a series of rotatable index drums, ratchet wheels therefor, pivoted levers, one for 35 each drum, flexible connections between the levers and the ratchet wheels for rotating the drums, pawls normally engaging said ratchet wheels to direct their rotation in one direction only, interconnecting means between the drums comprising pins on the drums, pivoted plates having fingers in the paths of said pins and pawls in the paths of the next adjacent ratchet wheels, a pivoted bar connected to all the pawls, a frame arranged to engage all the operating levers simultaneously and to also engage the pivoted bar connected to the pawls, and springs for returning the parts to normal position after being moved out of normal position.
10. A calculating machine comprising a series of rotatable drums, a ratchet wheel for each drum fast to the 40 same at one side thereof, a pin projecting from the other side of the drum, a spring-retained pawl for each ratchet wheel, a spring-retained plate for each drum having a finger in the path of the pin thereof and a spring-retained pawl in normal engagement with the ratchet wheel of the 45 next adjacent drum, a series of spring-retained segmental actuating levers having curved faces provided with finger-pieces, chain connections fast at one end to each lever and at the other end to a spring-controlled arm and passing over and in operative relation to the ratchet wheel of a 50 corresponding index drum, a pivoted bar connected to all the pawls, and a pivoted arm movable into contact with all the levers to impel them simultaneously in one direction against the action of their return springs and provided with cam faces engaging the pawl-actuating bar. 55
- In testimony that I claim the foregoing as my own, I have hereto affixed my signature in the presence of two witnesses.
